UNITED STATES PATENT OFFICE.

HUBBARD D. B. WILLIAMS, OF MANSFIELD, OHIO.

STORE-SERVICE APPARATUS.

SPECIFICATION forming part of Letters Patent No. 516,461, dated March 13, 1894.

Application filed May 15, 1893. Serial No. 474,333. (No model.)

To all whom it may concern:

Be it known that I, HUBBARD D. B. WILLIAMS, a citizen of the United States, residing at Mansfield, in the county of Richland and State of Ohio, have invented certain new and useful Improvements in Store-Service Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to store service apparatus, and aims to improve and increase the efficiency of this class of apparatus; the present invention being largely an improvement on the store service apparatus for which on 20 April 1st I filed an application for Letters Patent, Serial No. 468,668.

The invention will be more particularly set forth hereinafter and illustrated in the accompanying drawings, in which—

25 Figure 1 is a side elevation showing the application of the invention; before either end of the track wire has been lowered. Fig. 2 is a side elevation of a modified form of hanger having an independent guide rod for the propelling bar. Fig. 3 is a side elevation of a further modification showing the guide rod adjustable to and from the perpendicular independently of the hanger. Fig. 4 is a side elevation of a hanger showing a still further 30 modification. Fig. 5 is a detail view of the coupling ends of the sections constituting the hanger. Fig. 6 is an end view of the retainer. Fig. 7 is an enlarged detail view of the rod N and the parts through which it 35 passes. Fig. 8 is a detail view of the retainer.

Similar letters and numerals in the several figures refer to corresponding parts.

The hangers at the ends of the main or 45 track wire M are preferably formed of two sections or parts C and C', which have their inner or opposing ends pivotally connected by a screw-bolt 2, which passes through the approximately circular or expanded ends of 50 the said parts, the latter being serrated on their meeting sides to prevent the parts from

slipping after they have been adjusted and the bolt 2 is screwed up tight. The lower ends of the hangers are braced by suitable guys 3. Castings I and J are attached to 55 the hangers to form supports for the propelling bars E. Grooved pulleys 4 arranged at the inner ends of the supports or castings I and J receive the propelling bars E and relieve the friction when said bars are moved 60 vertically. If it is preferred to use a cord, as 7, to operate the bar E, the castings I and J will be extended and provided at their outer ends with guide pulleys 5 and 6, the cord or rope 7 being attached at its lower end 65 to the bar E and passing up over pulley 5 and down through casting I within convenient reach as shown to the right in Fig. 1.

The motor wire 8 for propelling the car 9, is attached to the inner end of the arm F of the 70 propelling bar E, and to the line or track wire M at a distance from the hanger. A slide G is placed on the hanger and to it is fastened the main line wire. A roller g, journaled in the outer part of the slide, travels on the 75 hanger to relieve friction when moving the slide vertically by suitable means. I preferably employ the vertical rod N, which passes through the casting I and has its upper end swiveled or pivotally mounted in the slide: 80 this rod having projections n near its upper and lower end which are adapted to engage in a slot or recess i in the casting I; so that by turning the rod N by the handle A at its lower end to free its projections n from 85 recess i it may be raised, thus raising the slide G, and locked in that position by turning it to bring its lower projection n into the recess i; or the rod and slide may be lowered and secured in that position by engaging the upper projection n in the recess i. A 90 spring O mounted on the hanger between the arm F and slide G forms a cushion for the arm F when the bar E drops after being elevated, and at the same time keeps the wires 95 8 and M slightly separated at their ends to form a brake to stop the car as it approaches the terminus of the line, as will be readily understood.

The retainer, a device to temporarily hold 100 the car at the end of the line, is composed of an arch or inverted U shaped piece 10, par-

allel wires 11 attached at their outer ends to the arch piece 10 and at their inner ends to the arm F. The arch piece 10 is arranged at right angles to the track wire M, and is provided with lugs 13 to which a gate 12 is hinged. This gate has a notch 14 in its lower edge to receive the motor wire 8, and is constructed of noiseless material. As the car approaches the end of the line it rides under the gate, raising the free lower end of the latter, which then closes or drops and retains the car in place. On elevating the propelling bar E the retainer is simultaneously raised, and releases the car, which is propelled by the angular separation of the motor and track wires, as will be readily understood.

When desired, a guide rod K may be employed to support the propelling bar, the grooved rollers 15 being interposed between 20 the guide rod and propelling bar, the latter fitting in the grooves of said rollers, where it is held by the tension of the motor wire. The journals of the rollers 15 travel on the outer side of the vertically slotted guide-rod in the 25 same manner set forth in my previous application before referred to. This guide rod K may be relatively fixed as shown in Figs. 2 and 4, or pivoted as shown in Fig. 3. In the latter case the guide rod is pivoted to the 30 lower casting I, and the upper casting J is slightly curved and slotted longitudinally; and the upper end of the guide-rod is secured thereto in the required position to which it may be adjusted by a screw-bolt j passing 35 through said slot. It will be seen that by having the lower portion of the hanger, or the guide rod K, adjustable to and from the perpendicular, that the track can be readily adapted for up or down grades, or a horizontal line; this being an important feature of 40 my invention.

In Fig. 4 is shown a construction to prevent the slipping of the rollers or grooved wheels 15; which consists in cog teeth 16 on the sides of said rollers or wheels and a rack 17 for the cog teeth 16 to mesh into. The journals of the rollers or wheels 15 travel on plain bearing surfaces 18 on the sides of the racks 17, the racks being arranged farther in than the 45 plain bearing surfaces, as shown in the said view.

To adapt the track wire to the grade the lower portion of the hanger, or the guide rod K, is adjusted to or from the perpendicular 55 in the manner before described, and said track wire is raised or lowered by means of the rod N and slide G. To propel the car the propelling bar E is raised which separates the wires 8 and M and drives or propels the car 60 in the manner which will be readily comprehended. As the car reaches the other end of the line its speed will be gradually checked by the slight separation of the ends of the wires 8 and M due to the spring O, as before 65 set forth. As the car nears the end of its travel it will compress the wire 8 down upon

the track wire and ride under the pivoted gate 12, the latter closing behind the car and retaining the same at the end of the line against the tension of spring O and the motor 70 wire.

Having thus described my invention, what I claim, and desire to secure by Letters Patent, is—

1. In a store service apparatus, the combination of a hanger, and a propelling rod having the motor wire attached thereto and means for adjusting said propelling rod to and from the perpendicular, substantially as and for the purpose set forth. 75

2. In a store service apparatus, the combination of a hanger, a guide rod adjustable to and from the perpendicular, guide rollers movable on the guide rod, and a propelling bar having the motor wire attached thereto 80 and movable vertically over the said guide rollers, substantially as set forth.

3. In a store service apparatus, the combination of a hanger composed of sections which have their meeting ends expanded and 85 serrated on the inner sides, a threaded bolt passing through the expanded ends to hold the sections together in the adjusted position, the track wire attached to the hanger, and a propelling rod having the motor wire connected 90 therewith, substantially as set forth.

4. In a store service apparatus, the combination of a hanger, a slide movable on the hanger and having the track wire connected therewith, a propelling rod, and a motor wire 100 attached to and movable with the propelling rod, substantially as set forth.

5. In a store service apparatus, the combination of a hanger, a slide movable on the hanger and having the track wire attached 105 thereto, a propelling rod having an arm which extends over the said slide and has the motor wire connected therewith, and a spring disposed between the said arm and slide, substantially as set forth for the purpose specified. 110

6. In a store service apparatus, the combination of a hanger having a casting provided with a slot or depression, a slide movable on the hanger and having the track wire attached thereto, and a rod passing through the 115 said casting and attached to the said slide, and having lateral projections which are adapted to be engaged with the said slot or depression on turning the rod, to hold the slide at the desired elevation, substantially as 120 described.

7. In a store service apparatus, the combination of a hanger having the track wire attached thereto, a guide rod having a straight bearing surface, and having cog teeth, guide 125 rollers movable over the guide rod and having their journals traveling on the said plain bearing surface and having cog teeth which mesh with the cog teeth of the guide rod, and a propelling rod movable on the guide rollers, 130 and having the motor wire attached thereto, substantially as set forth.

8. In a store service apparatus, the combination of a hanger, the track wire attached to the hanger, a propelling bar having an arm, and having the motor wire attached thereto, 5 a retainer carried by and movable with the propelling bar, and having a gate to close behind the car, and a spring to support the propelling bar in its lowest position and hold the motor and track wires separated at their ends

to form a brake for the car, substantially in 10 the manner set forth.

In testimony whereof I affix my signature in presence of two witnesses.

HUBBARD D. B. WILLIAMS.
